UNITED STATES PATENT OFFICE

2,365,452

BOOKRACK

Leslie H. Burlin, Valparaiso, Ind., assignor to Milton L. Sturm, Evanston, Ill., doing business as Milton Sturm & Company, Chicago, Ill.

Application April 6, 1943, Serial No. 482,028

3 Claims. (Cl. 211—43)

This invention relates to racks for receiving books, magazines or the like, and particularly to such book racks as are of small size to receive a few books or magazines and hold them in a convenient or handy position.

It is one of the objects of the present invention to provide a small portable book rack with book ends which will maintain a continuous pressure upon the last book of the group to hold all of the books of the group in an upright position and to maintain the books in such position as successive books are removed from the rack.

It is a further object of the present invention to provide such a book rack wherein the pressure that is applied to the last book of the stack for holding it vertical will be applied thereto at substantially the same distance from the base, regardless of how few or how many books there are on the rack.

It is a still further object of the present invention to provide a simple and economical book rack construction of the above mentioned character wherein a continuous spring pressure is maintained on the last book of the stack and yet will not require the use of metal springs.

It is a still further object of the present invention to provide a book rack of the above mentioned character which may be made substantially entirely of wood, so that with the exception of a few screws (which may also be replaced by wooden pins) the entire book rack may be made of wood.

The attainment of the above and further objects of the present invention will be apparent from the following specification taken in conjunction with the accompanying drawing forming a part thereof.

In the drawing:

Figure 1 is a longitudinal sectional view through a book rack embodying the present invention, said view being taken along the line 1—1 of Figure 2;

Figure 2 is a bottom plan view of the rack of Figure 1; and

Figure 3 is a fragmentary sectional view taken along the line 3—3 of Figure 1 and looking in the direction of the arrows.

Like reference numerals in the various figures designate like parts.

The book rack of Figure 1 consists of a base 1 in the form of a flat rectangular wooden board which rests on an open rectangular frame 2—2. The underside of the flat base 1 has a rectangular wooden bar 3 secured thereto in any desired manner as, for instance, by a pair of screws 4—4.

The bar 3 extends longitudinally of the base centrally thereof and for the major portion of the length of the base. A central flat wooden partition 6 extends across the top of the base 1 at the center thereof. To facilitate securing the partition 6 in place the base 1 is provided with a rectangular slot 7 through which a tongue 8 at the bottom of the partition 6 extends. The bar 3 is slotted for receiving the tongue 8 of the partition 6. A screw 10 extends through the bar 3 into the partition 6 for firmly securing the partition in place. Since the tongue 8 fits snugly in the slot 7 of the base 1 the partition 6 is held by the slot against turning and therefore a single screw 10 is sufficient to hold the partition firmly in place. The tongue fits firmly in the groove in the bar 3 and is thus held vertically.

A pair of identical end members 12—13 extend through slightly oversized slots 14 in the base 1. Each member 12—13 is bifurcated at its lower end, as indicated at 15—15, to embrace the bar 3, and is pivoted to the bar by dowel pins 16. A pair of similar flat wooden spring strip members 20—20 are secured to blocks 21—21 fastened to the underside of the base 1 on opposite sides of the longitudinal center thereof. Each spring member extends from its block 21 at one end of the base towards the opposite end 30 of the base where it bears upwardly against a pin 23 secured to the opposite end member 12 or 13, as the case may be. The wooden spring member 20 of Figure 1 is secured to the block 21 at the left hand side of Figure 1 by a screw 24 which maintains the spring 20 in the position illustrated in Figure 1. When the member 13 is turned about its center 16 in a clockwise direction the pin 23 forces the right hand end of the corresponding spring member 20 downwardly so that the spring member acting on the pin 23 constantly forces the end member 13 toward the partition 6. It is to be noted that the spring member 20 is held at one end by the screw 24 and that the corner of the associated block 21 acts as a fulcrum for the spring member 20. By tightening the screw 24 the tension on the spring member is increased so that the pressure on the spring member against the pin 23 is increased.

Books, magazines, or the like may be placed against either side of the partition 6 and are pressed against that partition by the curved end 26 of the end member 12 of the corresponding end member 13. As the number of books or papers in place is increased the corresponding end

member 12 or 13 swings outwardly from the partition 6 and the curve 26 maintains a continuous pressure against the last book or magazine in the rack. The part 26 is of such curvature that as the end member 12 or 13 is swung outwardly from the partition 6, as by the placing of more books on the rack, the curve 26 maintains contact with the last book in the rack always at approximately the same height from the base 1. The end member 13 is curved at 27 along a radius centered at 16 whereby the back of the opening 14 in the base is maintained closed by the end member 13 as it swings about its center 16. This results in the maintenance of a neat appearance of the book end for all positions of the members 12-13.

In compliance with the requirements of the patent statutes I have here shown and described a preferred embodiment of my invention. It is, however, to be understood that the invention is not limited to the precise construction here shown, the same being merely illustrative of the principles of the invention. What I consider new and desire to secure by Letters Patent is:

1. A book rack comprising a supporting structure including a base, a stationary vertical partition secured to the structure and extending across and above the base, an end member pivoted on the structure below the base and extending upwardly through an opening in the base, the portion of the end member that extends through the opening substantially filling said opening and being curved along arcs centered at the pivot center of the end member, spring means urging said end member towards said stationary vertical partition, and into engagement therewith, the part of the end member that engages the vertical partition being curved along an arc such that upon pivoting of the end member away from

the partition its points of tangency with a vertical plane remains at substantially the same distance from the base.

2. A rack for books or the like comprising a base, a central vertical partition extending across the base and including a tongue extending through an opening in the base, a bar secured to the under side of the base and having a slot into which the tongue extends, said bar extending longitudinally of the base centrally thereof, end members pivoted to the ends of the bar and extending upwardly through openings in the base and adapted to bear against the end books that may be positioned on the base, flat spring strips on opposite sides of the bar and each secured at one end to a fixed portion of the rack and bearing at its opposite end against an end member to urge the end member towards the central vertical partition.

3. A rack for books or the like comprising a base, a central vertical partition extending across the base and including a tongue extending through an opening in the base, a bar secured to the under side of the base and having a slot into which the tongue extends, said bar extending longitudinally of the base centrally thereof, end members pivoted to the ends of the bar and extending upwardly through openings in the base, flat spring strips on opposite sides of the bar and each secured at one end to a fixed portion of the rack and bearing at its opposite end against an end member to urge the end member towards the central vertical partition, each end member being curved at the part thereof that passes through the opening in the base along a curvature centered at its pivot with the bar.
